SERIES-PARALLEL CENTRIFUGAL PUMP

Aladar Hollander, Los Angeles, Calif., assignor to
 Byron Jackson Co., Huntington Park, Calif.,
 a corporation of Delaware

Application April 26, 1938, Serial No. 204,347

9 Claims. (Cl. 103—106)

This invention relates to improvements in multistage, two-shaft centrifugal pumps of the type wherein the stages are arranged in groups which may be connected together either in series or in parallel. This type of pump is particularly adapted for use as a fire pump, being compact and light in weight and capable of delivering either a large volume of liquid at low pressure or a small volume at high pressure.

10 Fire pumps are frequently required to operate against a relatively high suction lift, which causes cavitation if the first stage impellers rotate too fast. This defect can be overcome, without decreasing the pump capacity, by rotating the suction impellers at lower speed than the higher stage impellers. By mounting the first stage impeller of each group on a low speed shaft and the remaining impellers on a high speed shaft, the capacity of the pump may be materially increased while maintaining the diameter, and therefore the weight, within allowable limits.

15

In series-parallel, two-shaft pumps a cross-over valve is employed to connect the discharge from the last stage of one group either to the discharge header, when operating the groups in parallel, or to the inlet of the first stage of the other group, when operating the groups in series. In prior pumps the location of the cross-over valve has been more or less haphazard, no special consideration having been given to its location.

20 A principal object of this invention is to so arrange the various stages that the cross-over valve is located at a more convenient point, particularly from a standpoint of economy of manufacture and ease of assembly and repair.

25 A further object is to provide a series-parallel, two-shaft pump having a casing split in the plane of the shafts, and a cross-over valve having its axis in the parting plane.

30 A still further object is to provide an improved arrangement of the stages of a pump of the aforementioned type, whereby a more compact and lighter weight pump is made possible.

35 Other objects and advantages will be apparent from the following description, taken in conjunction with the accompanying drawings, wherein:

Fig. 1 is a plan view of a pump constructed in accordance with this invention;

50 Fig. 2 is a side elevation of the pump shown in Fig. 1;

Fig. 3 is an end elevation of the pump, as viewed from the left of Fig. 1;

55 Fig. 4 is a horizontal sectional view taken in

the plane of the shafts, as indicated by section line 4—4 of Fig. 2;

Fig. 5 is a vertical sectional view taken in the axial plane of the high-speed shaft, as indicated by line 5—5 of Fig. 4;

Fig. 6 is a vertical sectional view taken in the axial plane of the low-speed shaft, as indicated by line 6—6 of Fig. 4;

Fig. 7 is a transverse section taken on line 1—1 of Fig. 4;

Fig. 8 is a transverse section taken on line 8—8 of Fig. 4; and

Fig. 9 is a transverse section taken on line 9—9 of Fig. 4.

Referring to the drawings, the pump casing is shown as comprising an upper section 1 and a lower section 2, having a parting plane extending through the axes of the impeller shafts 3 and 4. Cast integral with the upper casing section are a discharge manifold 5 and a double suction 20 manifold 6. As shown in Fig. 1, the suction manifold is formed with two fluid passages 7 and 8, the passage 7 being provided with an inwardly opening check valve 10 at each end.

25 Suction passage 8 communicates with the suction inlet 12 of the first stage impeller 13 of one group, and the suction passage 7 communicates with the suction inlet 14 of the first stage impeller 15 of the other group. The impellers 13 and 15 are mounted on the low-speed shaft 4, 30 and, as shown in Fig. 4, are of larger suction area and lower specific speed than the impellers mounted on shaft 3. As shown in Fig. 9, impeller 13 discharges through its volute 17 into the inlet 18 of impeller 19. The impeller 15 similarly 35 discharges through its volute 20 into the inlet 21 of impeller 22. The impellers 19 and 22 are mounted on the high speed shaft 3.

40 By arranging the first-stage impellers 13 and 15 face-to-face with their inlets between the impellers, and the second-stage impellers 19 and 22 back-to-back, the inlets of the latter are disposed in the same transverse planes as the impeller cavities of the former, resulting in a very compact arrangement. The second-stage impellers are preferably cast integral, as shown in Fig. 4.

45 Also mounted on the high speed shaft 3 is a pair of third-stage impellers 25 and 26. Impeller 19 discharges through passage 27 into the inlet 28 of impeller 25, and impeller 22 discharges through passage 29 into the inlet 30 of impeller 26. The impellers 25 and 26 are arranged back-to-back and, like the impellers 19 and 22, are cast integral. The impeller 26 discharges direct- 50

55

ly into the discharge header 5 through passage 32 (Fig. 7).

A two-way cross-over valve 33 is provided for selectively connecting the discharge of impeller 25 with the discharge header 5 or the inlet 14 of impeller 15. The valve is of the rotary type, with an axial inlet 36 in constant communication with the impeller cavity of impeller 25 through passage 37 (Fig. 8), and a lateral discharge port 38 selectively connectible with a passage 39 (Fig. 7) leading to the discharge header 5, or to a cross-over passage 40 leading to the inlet header 7.

The valve 33 is journaled in the casing sections 1 and 2 with its axis lying in the parting plane of the sections and coaxial with the low speed shaft 4. A valve stem 45 projects from one end of the valve through a removable end plate 46, and has an operating handle 47 keyed thereto. When the valve is rotated to the position indicated in Figs. 6 and 7, the impeller 25 discharges directly into the discharge header 5, and when rotated to the position indicated in Figs. 4 and 8 the impeller 25 discharges into the inlet of impeller 15.

Adjustable packing glands 50 are provided to seal the junctures of the shafts 3 and 4 and the pump casing. A packing gland 51 is also provided around the valve stem 45. The driving connections for the shafts have not been shown inasmuch as any desired form of driving means may be provided, so long as the shafts are driven at the proper relative speeds.

The mode of operation of the pump is as follows: If a large volume of liquid at relatively low pressure is desired, the cross-over valve is positioned as shown in Figs. 6 and 7, to connect the discharge of impeller 25 with the discharge header 5. The impellers are then divided into two groups of three impellers each, operating in parallel. Liquid is drawn into first-stage impeller 13 from suction passage 8 and is discharged into the inlet 18 of impeller 18. The latter discharges into the inlet 28 of impeller 25, which in turn discharges into the discharge header 5 through the cross-over valve 33. The impellers 15, 22, and 28 of the other group are similarly connected in series between the suction inlet 7 and the discharge header 5.

To provide a relatively small volume of liquid at high pressure, the valve 33 is turned to the position shown in Figs. 4 and 8, to connect the discharge of the third-stage impeller 25 of one group with the inlet of the first-stage impeller 15 of the other group. The two groups are thus connected in series to form a six-stage pump, the impellers 15, 22, and 28 constituting the fourth, fifth, and sixth stages, respectively. At this time the check valves 10 in the suction header swing to closed position.

The advantages of the stage arrangement and the location of the cross-over valve should be apparent from the foregoing description. By locating the valve with its axis in the parting plane of the pump casing sections and in axial alignment with one of the shafts, the valve cylinder may be bored when the shaft journals are bored, without changing the set-up, thereby reducing the manufacturing cost. The valve is made accessible for inspection and repair when the upper pump casing 1 is removed for inspection of the shafts and impellers. By removing the end plate 46, the valve and its chamber may be inspected without removing the upper pump casing section.

The stage arrangement shown affords a very

compact and light weight pump. All connecting passages between the headers 5 and 6 and the initial and final stage impellers are of minimum length, since the header 6 is disposed directly over the inlets of the first-stage impellers and the header 5 is directly above the discharge of impeller 26 and the outlet port of the cross-over valve. The cross connections between impellers 13 and 19, and 15 and 22, respectively, are also of minimum length. The decrease in weight resulting from the reduction in the length of the various connecting passages is a very decided advantage in fire pumps, for obvious reasons. It also effects a material reduction in the manufacturing cost.

By employing parallel shafts and dividing the impellers between the shafts the available lateral space on a fire truck is utilized to fullest capacity. As shown in Fig. 9, there is ample space between the side frames of the truck chassis for two parallel sets of impellers, and by utilizing this space to the full extent a large number of stages may be provided without unduly increasing the length of the pump.

The casting of the pump casing sections is greatly simplified by the arrangement shown, particularly with reference to the location of the cross-overs from one shaft to the other. The cross-overs from impellers 13 and 15 to impellers 19 and 22 are entirely in the lower half of the pump casing, while the suction and discharge headers or nozzles and the cross-over from impeller 25 to the valve 33 are located in the upper half.

While I have shown for purpose of illustration a pump embodying six stages connectible in series or in two parallel groups of three stages each, it will be understood that the invention is equally applicable to a pump having a different number of stages.

I claim:

1. In a series-parallel multistage centrifugal pump, casing means, a pair of spaced impeller shafts, a pair of suction impellers on one shaft, a pair of second-stage impellers on the other shaft and having their inlets substantially in planes including the impeller cavities of the suction impellers, the discharge from the suction impellers being connected respectively to the inlets of the second-stage impellers, a pair of third-stage impellers on said other shaft, the discharge from the second stage impellers being connected respectively to the inlets of the third-stage impellers, thereby forming a pair of three-stage groups of impellers, a cross-over from the third-stage impeller of one group to the suction impeller of the other group for connecting said groups in series, and a cross-over valve for controlling said cross-over, said valve being disposed substantially in axial alignment with said suction impeller shaft and opposite said third-stage impellers.

2. A pump as defined in claim 1, in which said casing means comprises sections having parting faces lying in a plane including the axes of said shafts, said valve being disposed with its axis in said plane.

3. In a series-parallel multistage centrifugal pump, casing means, a pair of spaced impeller shafts journaled therein, one of said shafts terminating within said casing a substantial distance from the end thereof, a plurality of groups of impellers on said shafts, the impellers of each group being connected in series, a cross-over from the final-stage impeller of one group to the first stage impeller of another group for connecting

said groups in series, and valve means in said casing for controlling said cross-over, said valve means being disposed in axial alignment with said one shaft between the end of said shaft and the adjacent end of said casing.

5 4. A pump as defined in claim 3, in which said valve means comprises a cylindrical bore in said casing coaxial with said one shaft, and a valve body rotatably mounted in said bore.

10 5. A pump as defined in claim 3, in which said valve means comprises a cylindrical bore in said casing between the end of said one shaft and the adjacent end of said casing, a valve body rotatably mounted in said bore, and a valve stem on said body projecting through said casing in coaxial 15 relation to said one shaft.

20 6. In a series-parallel multistage centrifugal pump, a pump casing, a low-speed shaft and a high-speed shaft journaled in said casing, a pair of suction impellers of relatively large suction 25 area secured to said low-speed shaft, a plurality of impellers of relatively small suction area secured to said high-speed shaft, said impellers being connected in two parallel groups with the impellers in each group connected in series, a cross-over from the final stage impeller of one group to the suction impeller of the other group, and valve means in said casing for controlling said cross-over, said valve means being disposed in axial alignment with said low-speed shaft.

30 7. In a multistage centrifugal pump, a pump casing, spaced impeller shafts journaled in said casing, a pair of suction impellers on one shaft, a pair of final-stage impellers on the other shaft and offset axially with respect to said suction 35 impellers, a cross-over connecting one of said final-stage impellers with one of said suction impellers, a cross-over valve controlling said cross-over, said valve being disposed in axial alignment with said suction impellers and laterally opposite said final-stage impellers, a pair of suction 40 nozzles extending across said casing in a direction transverse to the axes of said shafts and in superimposed relation to the suction eyes of said suction impellers and communicating therewith, and a discharge nozzle extending across said 45 casing generally parallel to said suction nozzles and in superimposed relation to the discharge volute of one of said final-stage impellers and in communication therewith, said discharge nozzle also extending directly above the outlet of said

50 valve and communicating directly therewith in one position of said valve.

8. A portable fire pump particularly adapted to be mounted on a fire truck, comprising a casing, a pair of parallel impeller shafts journaled in 5 said casing and adapted to be disposed longitudinally of said fire truck, one of said shafts being of greater length than the other and determining the longitudinal dimension of said casing, said other shaft terminating within said 10 casing a substantial distance from one end thereof, a plurality of impellers on each of said shafts, said longer shaft having a greater number of impellers than said other shaft and at least one of the impellers on said longer shaft being 15 disposed axially beyond the inner end of said other shaft, cross-overs in said casing connecting said impellers in a plurality of series groups, a cross-over valve in one cross-over adapted to selectively connect said groups in series or in 20 parallel, said valve being mounted in said casing in axial alignment with the shorter of said shafts and axially beyond the inner end thereof, said valve having a stem projecting through the adjacent end of said casing in coaxial relation to 25 said shorter shaft, the combined length of the shorter shaft, valve, and valve stem being substantially equal to the length of said longer shaft, whereby the overall length of the operating parts of said pump is divided substantially equally 30 between the two shaft axes and the overall length of the pump is thereby reduced to a minimum.

9. In a series-parallel multistage centrifugal pump, a casing, a pair of impeller shafts journaled in said casing on spaced axes, one of said shafts terminating within said casing a substantial distance from the end thereof, a plurality of groups of impellers on said shafts, the impellers of each group being connected in series and the final stage impellers of each group being mounted 35 on the other of said shafts and disposed axially 40 beyond the inner end of said one shaft, a cross-over in said casing connecting the final-stage impeller of one group with the suction impeller of another group, and a valve for controlling said 45 cross-over, said valve being mounted in said casing in axial alignment with said one shaft and axially beyond the inner end thereof and laterally opposite the final-stage impellers mounted on said other shaft.

ALADAR HOLLANDER. 50
